CLAIM

The ornamental design for a connector as shown and described.

DESCRIPTION

FIG. 1 is a perspective view of a connector shown in an unlocked configuration according to the new design;

FIG. 2 is a left side view thereof;

FIG. 3 is a top side view thereof;

FIG. 4 is a front side view thereof;

FIG. 5 is a back side view thereof;

FIG. 6 is a perspective view of the connector shown in a locked configuration;

FIG. 7 is a left side view thereof;

FIG. 8 is a top side view thereof;

FIG. 9 is a front side view thereof; and,

FIG. 10 is a back side view thereof.

The ornamental design which is claimed is shown in solid lines in the drawings. The broken lines in the drawings show portions that form no part of the claimed design.

1 Claim, 10 Drawing Sheets
